J. F. CALLAHAN.

HAND TRUCK.

APPLICATION FILED JAN. 12, 1918.

1,342,585.

Patented June 8, 1920.

Inventor:
John F. Callahan,
By Frank C. Curtis,
Attorney

UNITED STATES PATENT OFFICE.

JOHN F. CALLAHAN, OF SCOTIA, NEW YORK; SARAH DE WAN CALLAHAN ADMINISTRATRIX OF SAID JOHN F. CALLAHAN, DECEASED.

HAND-TRUCK.

1,342,585.

Specification of Letters Patent. Patented June 8, 1920.

Application filed January 12, 1918. Serial No. 211,493.

To all whom it may concern:

Be it known that I, JOHN F. CALLAHAN, a citizen of the United States, residing at Scotia, county of Schenectady, and State of 5 New York, have invented certain new and useful Improvements in Hand-Trucks, of which the following is a specification.

Reference may be had to the accompanying drawings, and the reference characters 10 marked thereon, which form a part of this specification. Similar characters refer to similar parts in the several figures therein.

The principal object of the invention is to provide a hand-truck whereby packages 15 can be readily removed from a floor and transported without substantial change in the upright position of the package.

Other objects will appear in connection 20 with the following description.

Figure 1 of the drawings is a view in side elevation showing a hand-truck embodying my invention in the operation of loading thereupon a box or similar package, and indicating by dotted lines the position 25 of the truck and package in transit.

Fig. 2 is a top plan view of the same.

Fig. 3 is a perspective view of a broken-away part of the truck-body showing a modified form of take-up mechanism for the 30 hook which engages the upper front portion of the package.

Fig. 4 is a view in perspective of the hook for supporting the upper front end of the package.

Fig. 5 is a view in perspective of the brace, which prevents the package from falling back upon the body of the truck.

Referring to the drawings wherein the invention is shown in preferred form, 1 is 40 the body of the truck, the forward end of which is mounted upon wheels, 2. A package-supporting shoe, 3, projects from the front end of the truck-body, preferably in a plane substantially parallel with the truck-body.

At the inner end of the shoe, 3, an abrupt shoulder, 4, is formed adapted to engage the lower rear corner of a box or similar package, 5, in the manner shown in Fig. 1, 50 the lower rear corner of the box, thus resting in the angular seat formed by said shoulder and the inner end of the shoe, 3, and being prevented from rearward movement by said shoulder, 4.

55 A member, 6, preferably in the form of

a double-pointed hook, is adapted to engage the upper front corner-portion of the box, 5, to prevent forward movement thereof.

This member or hook, 6, has an adjustable connection, 7, with the body of the truck, 60 said connection being preferably in the form of a chain, the links of which are engageable with a claw, 8, fixed upon the body of the truck.

In place of the chain or claw any other 65 form of adjustable connection may be employed, as for example a cable adapted to be wound up on a drum, 10, controlled by a pawl-and-ratchet, 11, mounted on the truck-body, as shown in Fig. 3. 70

In the operation of the device, the shoe, 3, is forced beneath the rear corner of the box, for which operation the box may be tilted slightly forward, so that the lower rear corner may be seated in the angle between the shoulder, 4, and the inner end of the shoe, as shown in Fig. 1, and the hook, 6, is placed in engagement with the upper front corner-portion of the box, and the chain, 7, is drawn taut in engagement with 75 the claw, 8, thereby preventing any forward movement of the upper end of the box relatively to the truck-body.

The rear end of the truck-body is then forced down, causing the box to be raised 80 from the floor until the box assumes its normal upright position, in which position it can be maintained in transit from place to place.

To further support the box and prevent it 85 from swaying out of substantially upright position, I provide means for supporting the rear side of the box at a point substantially above said shoulder, 4, which prevents the box from falling over upon the body of the 90 truck, and holds the box upright.

I have shown for this purpose a brace, 12, in the form of a yoke pivotally mounted at 13, upon the body of the truck, which brace is adapted to be swung to and from 100 a forwardly-and-upwardly inclined position to engage the rear side of the box, 5, at a point above the shoulder, 4, as shown by solid lines in Fig. 1.

If the nature of the package is such that 105 the brace, 12, is not required, it can be swung back out of the way to the position indicated by dotted lines in Fig. 1.

I have shown the rear end of the truck-body upwardly offset at 14, and provided 110

- with a handle, 15, which by reason of said offset is conveniently located to be grasped by the user of the truck standing erect in moving the truck from place to place.
- 5 I have shown the shoe, 3, formed with spurs or points, 16, adapted to be driven sufficiently into a box or similar package to support the lower rear corner of the package when it is found inconvenient to raise 10 the lower rear corner to permit the shoe to be inserted therebeneath. In this use of the shoe, the truck is forced against the lower rear side of the package to drive the spurs, 16, thereinto. The hook, 6, is placed in engagement with the upper front corners of 15 the package, adjustable connection, 7, is taken up taut, and the package is then raised slightly from the floor and transported to the desired place in substantially the 20 manner above described, the only difference being that the lower rear corner is supported by the spurs, 16, instead of by the angular seat formed between the shoulder, 4, and the inner end of the shoe.
- 25 It is characteristic of my invention that the truck has means for engaging the rear side of the package at a substantial distance above the angular seat for the lower rear corner of the package when the package is substantially erect, and when the 30

body of the truck is in normal traveling position, and in addition to this has adjustable means connected with the truck-body and engageable with the front side of the package when in upright position with 35 the body of the truck in normal traveling position, as a result of which the package is supported in erect position against either forward or rearward movement in the normal traveling position of the truck. 40

What I claim as new and desire to secure by Letters Patent is—

In a hand-truck and in combination, a wheel-supported body having on its front end means for engaging and supporting the 45 lower rear corner of a package; a member adapted to engage the upper front portion of said package having an adjustable connection with the truck-body; and means for supporting the rear side of said package at 50 a point substantially above its lower rear corner with the package in substantially upright position and with the handle-portion of the truck-body in substantially horizontal position. 55

In testimony whereof, I have hereunto set my hand this 31st day of December, 1917.

JOHN F. CALLAHAN
